US00D892065S

(12) **United States Design Patent** (10) Patent No.: **US D892,065 S**
(45) Date of Patent: **** Aug. 4, 2020**

(54) **REMOTE CONTROL DEVICE**(71) Applicant: **Lutron Technology Company LLC**,
Coopersburg, PA (US)(72) Inventors: **Chris Dimberg**, Easton, PA (US);
Jason C. Killo, Emmaus, PA (US);
Matthew Philip McDonald,
Phoenixville, PA (US); **Daniel L. Twaddell**, Allentown, PA (US)(73) Assignee: **Lutron Technology Company LLC**,
Coopersburg, PA (US)(**) Term: **15 Years**(21) Appl. No.: **29/705,783**(22) Filed: **Sep. 16, 2019****Related U.S. Application Data**

(63) Continuation of application No. 29/640,708, filed on Mar. 16, 2018, now Pat. No. Des. 865,682, which is a continuation of application No. 15/469,459, filed on Mar. 24, 2017, now Pat. No. 10,109,181.

CLAIM

The ornamental design for a remote control device, as shown and described.

DESCRIPTION

FIG. 1 is a perspective view of a remote control device showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken lines illustrate structure or features which form no part of the claimed design.
